MAGNET-ACTUATED COUPLER FOR MODEL
RAILROAD CARS

Clarence K. Edwards, 1409 Kings Highway, and Lawrence D. Edwards, 1016 Winchester Ave., both of Medford, Oreg.

Filed Sept. 28, 1959, Ser. No. 842,925
7 Claims. (Cl. 213—212)

This invention relates to couplers for model railroad cars, particularly to couplers of the class actuated by magnetic forces.

It is the general object of the present invention to provide a car coupler for model railroads which makes possible positive coupling and uncoupling of the cars from a remote station.

It is another important object of the present invention to provide a coupler for model railroad cars which will not inadvertently become uncoupled as the cars move along the tracks, but which can easily be operated upon arresting or reversing the forward motion of the cars.

A further object of the invention is the provision of a model railroad car coupler which is simple in construction, easily applied to cars of various categories, and not subject to mechanical interference from any other element except that of other couplers in the normal function of coupling.

The manner in which the foregoing and other objects of this invention are accomplished will be apparent from the accompanying specification considered together with the drawings, wherein:

FIG. 1 is a view in side elevation of a pair of railroad cars coupled together with the herein described couplers;

FIG. 2 is a detail view in side elevation, partly in section, of the herein described coupler;

FIG. 3 is a plan view of the coupler, partly in section, illustrated in a position of incipient uncoupling;

FIGS. 4, 5, and 6 are views corresponding to FIGS. 1, 2, and 3 but illustrating the construction of the herein described coupler in an alternate form;

FIG. 7 is a plan view of a magnet for use with the embodiment of FIGS. 1-3 and showing the pole arrangement and flux pattern with a magnetic element positioned for attraction to the magnet;

FIG. 8 is a sectional view taken along the line 8—8 in FIG. 7;

FIG. 9 is a plan view similar to FIG. 7 and showing the flux pattern with the magnetic element in its final position of attraction; and

FIG. 10 is a sectional view taken along the line 10—10 in FIG. 9.

Generally stated, the coupler of our invention comprises a drawbar, means mounting the drawbar on the end of the car for transverse pivotal movement, a coupler head on the outer end of the drawbar, and a magnetic member carried by the coupler head. The magnetic member upon being actuated by a magnetic field of force arranged transversely or in parallel, as the case may be, beneath the car acts to pivot the coupler head and drawbar to a position of car uncoupling. Resilient means are provided for opposing this pivotal action, thereby returning the assembly to car coupling position when the force of the magnetic field is no longer exerted.

2

In the form of the invention illustrated in FIGS. 1-3, cars 10 mounted on trucks 12 move on tracks 14. Couplers indicated generally at 16 are mounted one on each end of each car. For this purpose a hollow box 22, open at its outer end, is longitudinally extended either as an attachment or as part of the underframe.

An internally threaded hollow post 24, which may be formed integrally with the top of the box, extends downwardly. The lower side of the box is closed by means of a plate 26 held in place by a screw 28, the threads of which engage those in hollow post 24.

The inner end of a drawbar 30 is journaled on post 24. It carries an inwardly projecting tab 32 against which presses a compression spring 34, the purpose of which is to urge the drawbar continuously toward a coupling position.

The outer end of the drawbar supports a coupling head or knuckle 36. This member is formed with an inwardly directed, transversely disposed hook 38 and an outwardly projecting, transversely disposed arm 40. It will be observed that the configuration of hook 38 is such that adjacent cars can not be uncoupled as long as a pulling force is applied to the drawbar. It is to be noted further that the outermost end of drawbar 30, comprising an edge of arm 40 is curved, with the general direction of curvature being at an angle relative to the longitudinal center line of the cars, thus providing a cam surface for guiding the couplers of adjacent cars into automatic coupling engagement with each other.

Extending downwardly from the coupler head is a bracket 42 which supports a vertically extending pin 44. This pin comprises a magnetic member the lower end of which closely approaches the surface of tracks 14, and which is used for actuating the coupler to a position of uncoupling.

Thus, located between tracks 14 in a selected location is a permanent or electromagnet 46. Preferably, it is a permanent magnet of the ceramic type. Whatever its class, it is magnetized with multiple poles, i.e., North—South—North—South—North—South, running parallel to the rails as indicated in FIG. 3.

The magnetic elements 44 normally are located off center with respect to the longitudinal center line of the magnet 46 when the cars are coupled together. The uncoupling operation is effected by stopping the cars with the interconnecting couplers located over the magnet 46, and then reversing the forward car sufficiently to disconnect the hooks 38, as illustrated in full lines in FIG. 3.

The magnetic elements 44 thereupon automatically move inward toward the longitudinal centerline of the magnet against the tension of springs 34. This movement is believed to be caused by the magnetic action illustrated in FIGS. 7-10, as follows:

In FIG. 7 the magnetic element 44 is shown in position displaced to the right of the longitudinal centerline of the magnet 46 but within the magnetic field of the latter. Since the magnetic element is much more permeable than air, the magnetic lines of force are therefore influenced by the proximity of the element and redirect themselves so that as many of them as possible permeate the element. Additionally, since magnetic lines of force seek to become as short as possible, they therefore cause the magnetic element 44 to be drawn inward toward the

centerline of the magnet, finally reaching a position (FIG. 9) in which a maximum number of magnetic lines of force pass through the element.

It will be understood that since the flux density of a magnet is greatest at the poles, the element 44 would be drawn in the longitudinal direction of the magnet toward the nearest pole if it were free to move. However, since it is connected to the railroad car it is not free to do so, and hence it will remain in whatever position it has been placed unless the flux density is sufficiently great to physically move the railroad cars. However, even though the magnetic element 44 may be located at a pole or somewhere between poles, it will nevertheless locate itself toward the longitudinal centerline of the magnet where it affords permeation by the greatest number of lines of force.

It will be understood that the force of springs 34 must not be sufficient to move the magnetic elements 44 outward from the coupling position shown in FIG. 3, against the inward attracting force of the magnetic field, for in such event the couplers will not uncouple. However, the force of springs 34 may be sufficient to substantially counterbalance the magnetic force tending to move the elements 44 inward. In such event, uncoupling is achieved by reversing the forward car until the curved arms 40 engage the cam surfaces 36 of the opposing coupling heads 36 and pivot the drawbars outward sufficiently to separate the hooks 38 laterally. The magnetic elements 44 are held in this position by the counterbalancing forces of the springs 34 and magnetic field, thereby allowing the couplers to be separated by longitudinal movement of the cars.

In the form of the invention illustrated in FIGS. 4-6, cars 50 having trucks 52 running on rails 54 are coupled together by couplers indicated generally at 56. The couplers are generally mounted one on each end of each car. For this purpose a hollow box 62 is longitudinally extended either as an attachment or as a part of the car underframe. An internally threaded hollow post 64, which may be formed integrally with the top of the box, extends downwardly. The lower side of the box is closed by means of a plate 65 held in place by a screw 66.

The coupler centering device, a flat plate of bronze spring, is cut away and bent inwardly at its terminal end to form spurs 68 which dig into the side wall of the box securing it in place. The side portions are cut away and bent upwardly to form leaf springs 70 which may press against the side walls of the box, resiliently urging a drawbar 66, mounted on post 67, to a center or coupling position.

A coupler head or knuckle indicated generally at 72 is mounted on the outer end of drawbar 66. It is formed in two parts. A first part 74 is rigid with the drawbar and is formed with a forwardly obliquely extending arm 76, the inwardly disposed surface of which is provided with a cam surface for guiding a companion coupler into coupling engagement.

The second section 78 of the coupling head is hinged to the first section by means of post 80. It is formed with a hook 82 arranged for interlocking with a similar hook on the companion coupler. As in the case of hooks 38 of the embodiment of FIGS. 1-3, the hooks are shaped in such a manner that they can not be separated as long as a pulling force is exerted on the drawbars. They are urged continuously into a position of hooking engagement by resilient means such as compression spring 84 interposed between the base of the hook and the forward end of drawbar 66.

Magnetic means are provided for swinging the pivoted segment of coupler 72 to uncoupled position. Such means in the illustrated form comprise a magnetic element which preferably comprises post 80 bent so that it extends forwardly and laterally of the car. Thus it is positioned off

center of the longitudinal center line of a permanent or electromagnet 36 which may be placed between rails 54. The poles of the magnet extend parallel to the rails, outwardly from the posts 80, so that the latter are caused to move outward toward the poles in opposite directions for uncoupling the couplers.

Thus when cars 50 traverse the magnet, magnetic elements 80 tend to swing outwardly, uncoupling the cars. Such uncoupling is not possible as long as a pulling force is exerted on the cars since hooks 82 remain securely interlocked.

However, if the cars are stopped and their motion reversed, with couplers 72 stationed above the magnet, the hooks are disengaged from each other so that the magnetic elements 80 are free to be moved outwardly by the attraction of the greater magnetic flux density at the poles. It is understood that springs 84 must be sufficiently weak to permit this movement. Thus the elements 80 move coupler elements 78 to which they are attached to positions of uncoupling, separating the cars.

Thus it will be apparent that by the present invention we have provided couplers of simple construction and positive action for model trains which may be employed for the automatic coupling or uncoupling of the cars. The couplers cannot become uncoupled while the train is in motion, nor can they be separated at any location other than the selected ones at which magnets are stationed. Furthermore, they are widely applicable to cars of any of the conventional classes.

It is to be understood that the form of our invention herein shown and described is to be taken as a preferred example of the same and that various changes in the shape, size and arrangement of parts, e.g. interchanging the relative positions of the magnet and magnetic member, may be resorted to without departing from the spirit of our invention or the scope of the subjoined claims.

Having thus described our invention, we claim:

1. A magnetic coupler for model railroad cars operating on a track, comprising a coupler member, means pivotally mounting the coupler member on an end of a car for horizontal transverse movement between car coupling and car uncoupling positions, resilient means operatively engaging the coupler member and urging the latter to car coupling position, a stationary magnet mounted below the coupler member adjacent the track, and a magnetic member secured rigidly to the coupler member and depending downwardly therefrom to a point capable of intercepting the magnetic field of the magnet, the magnetic member being disposed relative to said magnetic field when the coupler member is in coupling position such that the magnetic member is so influenced by said magnetic field as to afford movement of said magnetic member in a direction to move the attached coupler member to uncoupling position against the resistance of a resilient means.

2. The magnetic coupler of claim 1 wherein the magnet comprises an elongated body having a longitudinal axis arranged parallel to the car track and includes a plurality of longitudinally spaced pairs of poles extending transversely to said longitudinal axis.

3. The magnetic coupler of claim 1 wherein the magnet comprises an elongated body having a longitudinal axis arranged parallel to the car track and includes a pair of poles extending parallel to said longitudinal axis on opposite sides of the longitudinal center line of the magnet body.

4. The magnetic coupler of claim 1 wherein the coupler member mounting means comprises a drawbar supporting the coupler member at one end, and pivot means mounting the opposite end of the drawbar on the car for said horizontal transverse movement, and the resilient means interengages the drawbar and car.

5. The magnetic coupler of claim 1 wherein the coupler member mounting means comprises a drawbar

mounted at one end on the car, and pivot means mounting the coupler member on the opposite end of the drawbar for said horizontal transverse movement, and the resilient means interengages the coupler member and drawbar.

6. The magnetic coupler of claim 5 wherein the magnetic member comprises a downward extension of said pivot means, said extension projecting away from the axis of said pivot means, and said pivot means being secured to the coupler member for rotating the latter with said extension about the axis of said pivot means. 10

7. The magnetic coupler of claim 1 wherein the mag-

netic member comprises a pin extending vertically downward from the coupler member.
